UNITED STATES PATENT OFFICE

JOHN H. SHAW, OF NEW HAVEN, CONNECTICUT, ASSIGNOR TO SARGENT & COMPANY,
OF NEW HAVEN, CONNECTICUT

LOCK

Application filed March 7, 1929. Serial No. 344,973.

This invention relates to locks and it has especial reference to mortise locks of the type in which a latch bolt is provided which may be retracted from either the interior or 5 the exterior of the door.

One of the primary objects of the invention is to furnish a very simple, inexpensive and efficient mechanism for a lock of the general character stated.

10 Another object of the invention is to provide an improved form of lock of the above character in which means is provided for dogging the latch bolt against operation by the knob on the exterior of the door.

15 A further object of the invention is to provide key controlled means at the exterior of the door for releasing the exterior knob of the door from the dogging means whereby the latch bolt may be retracted by the knob.

20 To these and other ends, the invention consists in the novel features and combination of parts to be hereinafter described and claimed.

In the drawings,

25 Fig. 1 is a fragmentary view of the door having a lock according to my invention mounted therein;

Fig. 2 is an end view of the door shown in Fig. 1;

30 Fig. 3 is a view of the interior mechanism of the mortise lock, with the cap plate removed;

Fig. 4 is a sectional view along line 4—4 of Fig. 3;

35 Fig. 5 is a sectional view along line 5—5 of Fig. 1;

Fig. 6 is a view similar to Fig. 5, but showing certain parts of the lock mechanism in a different position;

40 Fig. 7 is a sectional view along line 7—7 of Fig. 5;

Fig. 8 is a sectional view along line 8—8 of Fig. 7; and

45 Fig. 9 is a sectional view along line 9—9 of Fig. 5.

Referring to the drawings in which I have illustrated my invention by showing a preferred embodiment of the same, the reference numeral 10 indicates, in general, a section 50 of a door having mounted therein a mortise

lock generally indicated by the reference numeral 11 and having a case 12, provided with a face plate 13 and a cap plate 14. Reference numeral 15 indicates, in general, a latch bolt having a head 16, a stem 17, and a crosshead 18, latch bolt 15 being constantly urged into protracted position by means of compression spring 19, received in an internal bore in stem 17, and bearing against post 20 on case 12. In an upper part of lock case 12, 55 a retracting lever 21 is pivoted, as at 22, lever 21 having an end 23 engaging crosshead 18. Pivotally supported on lever 21 at an intermediate point 24 is a link 25, link 25 being pivotally supported on a lever 26 at an intermediate point, as at 27. Lever 26 at its upper end is pivotally mounted on post 28 on case 12, and at its lower end is provided with a laterally extending arm 29 engageable by a plurality of rollbacks 30, 31 and 32, rollback 30 being provided with a preferably square or otherwise non-circular axial opening for the reception of a non-circular stem 33 of knob 34, which is on the inside of door 10. 60

Rollback 30 is counterbored, as at 35, for 75 the reception of hub 36 on rollback 31, while the latter is counterbored at 37 for the reception of hub 38 on rollback 32. Rollbacks 30 and 32 are provided on their outer ends with hubs 39 and 40 which are received in 80 oppositely disposed openings in case 12 and face plate 14. Rollbacks 31 and 32 are provided with square or otherwise non-circular openings for the reception of a non-circular stem 41 of knob 42, the latter being disposed 85 on the exterior of the door and secured to stem 41 in a manner to be hereinafter pointed out.

From the above description of the invention, it will be readily understood by one skilled in the art that rotation of knob 34 will result in the rotation of rollback 30, and through levers 26 and 21 the retraction of the latch bolt 15, while rotation of knob 42 will rotate rollbacks 31 and 32 and retract the 95 latch bolt in a similar manner.

In order that the latch bolt retracting mechanism may be dogged against operation from the exterior knob of the door, in the present instance knob 42, the rollback 31 is 100

provided with a pair of spaced shoulders 43 and 44, between which may be received the end of thumb slide 45, projecting through the face of the lock, thumb slide 45 being movable away from shoulders 43 and 44 by 5 means of a second thumb slide 46 likewise projecting through the face of the lock and connected to slide 45 by means of connecting lever or walking beam 47, fulcrumed on case 12, as at 48.

10 In order to hold the thumb slide 45 in dogging or releasing position slide 45 is provided with a pair of transverse notches 49 and 50 which are engageable by the curved 15 end of spring 51, the latter being bent about a post 52 on case 12 and having a hook-like end 53 engaging a post 54 on lock case 12, spring 51 passing between post 52 and thumb slide 45, slide 45 cooperating with posts 52 and 54 to hold the spring in the lock case. 20 It will be readily understood without further description that spring 51 acts as a detent to hold slide 45 at either end of its stroke.

Knob 42 is preferably hollow and has 25 mounted in the interior thereof a sleeve 55 in which is received a cylinder lock 56 having on a rearward part thereof a sleeve-like end 57 provided with an axially threaded opening 58 for the reception of the similarly 30 threaded end of stem 41. Stem 41 is provided with a preferably square bore in which is received a square rod 59, square rod 59 being connected to stem 33 by a swivel joint, as for example by a pin 60, pin 60 being rotatably received within axial openings in 35 rod 59 and stem 33 and being held against axial movement therein by means of grooves 61 and 62, which are near the ends of pin 60, the walls of stem 33 and of square rod 59 being struck inwardly into the grooves, as 40 at 63.

The arrangement is such that rod 59 and stem 33 are free to rotate on pin 60, but are held against axial movement thereon. Passing 45 through the stem 41 and through square rod 59 is a pin 65, stem 41 being provided with oppositely disposed longitudinally extending slots 66 which permit axial movement of stem 41 on square rod 59, for a purpose to 50 be hereinafter described.

Cylinder lock 56 comprises a key plug 67, a plurality of pin tumblers 68 controlling the rotation of the key plug, and a radially movable bolt 69, provided with an end 70 which is normally received in an opening 71 in sleeve 55. Bolt 69 at its upper end is provided with a bore 72 for the reception of a compression spring 73, one end of which bears against the bolt while the opposite end is received in an opening 74 in the cylinder lock 56.

Key plug 67 is provided on its end adjacent the bolt 69 with a crank pin or cam 75 which is received in a transverse slot 76 in bolt 69. 60 Upon the insertion of a key 77 having suit-

able notches to align the pin tumblers the key plug may be rotated, rotation of key plug 67 acting to withdraw head 70 of bolt 69 from opening 71 in sleeve 55 through the medium of cam 75 received in slot 76. In order to 70 limit rotational movement and to prevent axial movement of key plug 67 in cylinder lock 56, a threaded pin 78 is mounted in the cylinder lock and extends into a transverse slot 79 in key plug 67. Preferably, sleeve 55 is 75 mounted in knob 42 by means of threaded sleeve end 80, received in a threaded opening in the knob, rotation of sleeve 55 relatively to the knob 42 being prevented by one or more screws 81, partly in the sleeve and 80 partly in the knob. One or more screws 82 pass through knob shank 64 and into knob 42 to secure these parts rigidly together. Upon the withdrawal of bolt head 70 from 85 opening 71, cylinder lock 56 is free to move in an axial direction in sleeve 55, this movement being limited by screw 83 which passes through sleeve 55 and into axially extending opening 84 in cylinder lock 56.

The operation of the lock may be readily 90 understood from the above description, but will be briefly described as follows: Normally, the lock parts occupy the positions shown in Figs. 3 and 5 wherein stem 41 is shown received in the rollbacks 31 and 32. In this 95 position rotation of knob 42 through pin 65 and stem 41 will produce rotation of rollbacks 31 and 32 and through the medium of levers 21 and 26, the retraction of bolt 15. If it is desired to dog the latch bolt against 100 operation by knob 42, the thumb slide 45 may be pushed inwardly to bring its inner end between shoulders 43 and 44 of rollback 31, whereupon the latter is held against rotation. Since stem 41 is received in rollback 105 31, it will be readily understood that the knob 42 is now held against turning movement and the latch may not be retracted thereby.

If, however, a suitable key 77 is now 110 inserted in cylinder lock 56 and rotated, the bolt head 70 of bolt 69 may be withdrawn from opening 71, whereupon the cylinder lock may be moved axially in sleeve 55 into the position shown in Fig. 6, in which position stem 41 is withdrawn from rollback 31, slots 66 permitting relative axial movement between stem 41 and rod 59. The knob 42 may now be rotated and through the engagement of stem 41 with rollback 32 will retract 115 the latch bolt, as may be readily understood. The several parts of the lock may be left in this position as long as is desirable, and may be restored to dogged position by moving the cylinder lock axially inwardly in sleeve 55 120 and rotating key plug 67 to bring bolt end 70 into opening 71, whereupon the stem 41 is again in engagement with rollback 31 and the knob 42 dogged against operation.

125 In order to prevent shoulders 43 and 44 of

rollback 31 from getting out of alignment with thumb slide 45, and in order to properly align rollbacks 30, 31 and 32 a number of springs 85, 86 and 87 are mounted in a lower part of the lock case 12, springs 85, 86 and 87 being mounted in dove-tailed slots in post 88 on case 12 and having their outer ends in engagement with the lower flat faces 89 of rollbacks 30, 31 and 32.

- 10 From the above description of the nature of the invention and the preferred embodiment of the same, it will be readily understood that I have provided a relatively simple form of lock mechanism in which a knob 15 mounted on the exterior of the door may be dogged against operation and in which key controlled means is provided for releasing the exterior knob of the door from its dogged condition.
- 20 While I have shown a preferred embodiment of my invention, it is to be understood that the same is not to be limited to all the details shown but is capable of modification and variation within the spirit of the invention 25 and the scope of the appended claims.

I claim:

1. In a lock for a door or the like, a lock case, a latch bolt therein, a knob at the exterior of said door for retracting said latch bolt, means for dogging said knob against retraction of said latch bolt, and means at the exterior of the door for releasing the knob from control by the dogging means to permit the retraction of the latch bolt by said knob, 35 the dogging means remaining in dogging position during such release.
2. In a lock for a door or the like, a lock case, a latch bolt therein, a knob at the exterior of said door, a pair of rollbacks in the lock case, means connected to said knob and extending into said lock case to engage said rollbacks, means for dogging one of said rollbacks, and means at the exterior of the door for disengaging the first named means from the dogged rollback.
3. In a lock for a door or the like, a lock case, a latch bolt therein, a knob at the exterior of the door, a pair of rollbacks within the lock case for retracting said latch bolt, a stem for said knob extending into the lock case and normally engaging said pair of rollbacks, means for dogging one of said rollbacks against operation, and means at the exterior of the door for disengaging said stem from the dogged rollback.
4. In a lock for a door or the like, a lock case, a latch bolt therein, a knob at the exterior of the door, a pair of rollbacks within the lock case for retracting said latch bolt, a stem for said knob extending into the lock case and normally engaging said pair of rollbacks, means for dogging one of said rollbacks against operation, and key controlled means at the exterior of the door for

disengaging said stem from the dogged rollback.

5. In a lock for a door or the like, a lock case, a latch bolt therein, a knob at the exterior of the door, a pair of rollbacks within the lock case for retracting said latch bolt, a stem for said knob extending into the lock case and normally engaging said pair of rollbacks, means for dogging one of said rollbacks against operation, and key controlled means carried by the knob at the exterior of the door for disengaging said stem from the dogged rollback.

6. In a lock for a door or the like, a lock case, a latch bolt therein, a knob at the exterior of the door, a slideable stem on said knob, a pair of rollbacks within the lock case for retracting said latch bolt, said slideable stem having a permanent operative connection with one of said rollbacks and being movable into engagement with the other of said rollbacks, and means for dogging the last named rollback against movement by said stem.

7. In a lock for a door or the like, a lock case, a latch bolt therein, a knob at the exterior of the door, a pair of rollbacks within the casing for retracting said latch bolt, movable means connected to said knob and extending into the lock case and normally engaging both of said rollbacks to actuate the same upon rotation of the knob, means for dogging one of the rollbacks against actuation by the knob, and means for moving said movable means out of engagement with the dogged rollback.

8. In a lock for a door or the like, a lock case, a latch bolt therein, a knob at the exterior of the door, a pair of rollbacks within the case for retracting said latch bolt, movable means connected to said knob and extending into the lock case and normally engaging both of said rollbacks to actuate the same upon rotation of the knob, means for dogging one of the rollbacks against actuation by the knob, and means for moving said movable means out of engagement with the dogged rollback, said last named means comprising key controlled means carried at the exterior of the door.

9. In a lock for a door or the like, a lock case, a latch bolt therein, a knob at the exterior of the door, a pair of rollbacks within the case for retracting said latch bolt, movable means connected to said knob and extending into the lock case and normally engaging both of said rollbacks to actuate the same upon rotation of the knob, means for dogging one of the rollbacks against actuation by the knob, and means for moving said movable means out of engagement with the dogged rollback, said last named means including key controlled means carried by the knob at the exterior of the door for controlling the movement of said movable means.

10. In a lock for a door or the like, a lock case, a latch bolt mounted therein, a knob at the exterior of the case, a pair of rollbacks within the lock case for retracting the latch bolt, a slideable stem for said knob extending into the lock case and normally engaging said pair of rollbacks to retract the latch upon rotation of the knob, a cylinder lock mounted in the knob for axial movement therein, said cylinder lock being connected to the movable stem, and key operated means for controlling the movement of said cylinder lock in said knob, means for dogging one of said rollbacks against actuation, said cylinder lock upon movement in one direction moving the slideable stem out of engagement with the dogged rollback. 70
15. In a lock for a door or the like, a lock case, a latch bolt in said case, a rollback for retracting said latch bolt, a knob having a stem movable relatively to the knob, said stem in one position engaging said rollback to permit retraction of the latch bolt by the knob and in another position being free from engagement with said rollback, means for dogging the rollback against operation of the retracting mechanism, and key controlled means carried by the knob for controlling the movement of said stem. 80
20. In a lock for a door or the like, a lock case, a latch bolt in said case, a rollback for retracting said latch bolt, a knob having a stem movable relatively to the knob, said stem in one position engaging said rollback to permit retraction of the latch bolt by the knob and in another position being free from engagement with said rollback, means for dogging the rollback against operation of the retracting mechanism, and key controlled means carried by the knob for controlling the movement of said stem. 85
25. In a lock for a door or the like, a lock case, a latch bolt in said case, a rollback for retracting said latch bolt, a knob having a stem movable in an axial direction relatively to the knob, said stem in one position engaging said rollback to permit retraction of the latch bolt by the knob and in another position being free from engagement with said rollback, means for dogging the rollback against operation of the retracting mechanism, additional means operable by the knob for retracting the latch bolt, and key controlled means carried by the knob for controlling the movement of said stem. 90
30. In a lock for a door or the like, a lock case, a latch bolt in said case, a rollback for retracting said latch bolt, a knob having a stem movable in an axial direction relatively to the knob, said stem in one position engaging said rollback to permit retraction of the latch bolt by the knob and in another position being free from engagement with said rollback, means for dogging the rollback against operation of the retracting mechanism, additional means operable by the knob for retracting the latch bolt, and key controlled means carried by the knob for controlling the movement of said stem. 95
35. In a lock for a door or the like, a lock case, a knob mounted on the same, a cylinder lock in said knob, said cylinder lock being axially movable in said knob, a latch bolt in said case, latch retracting mechanism in the case, and means controlled by the axial movement of the cylinder lock in the knob for connecting said knob to an operative part of the latch retracting mechanism. 100
40. In a lock for a door or the like, a lock case, a knob mounted on the same, a cylinder lock in said knob, said cylinder lock being axially movable in said knob, a latch bolt in said case, latch retracting mechanism in the case, and a stem connected to said cylinder lock, said stem being adapted to be brought into operative engagement with an operative part of the latch retracting mechanism upon axial movement of the cylinder lock in the knob. 105
45. In a lock for a door or the like, a lock case, a knob mounted on the same, a cylinder lock in said knob, said cylinder lock being axially movable in said knob, a latch bolt in said case, latch retracting mechanism in the case, and a stem connected to said cylinder lock, said stem being adapted to be brought into operative engagement with an operative part of the latch retracting mechanism upon axial movement of the cylinder lock in the knob. 110
50. In a lock for a door or the like, a lock case, a latch bolt therein, a knob at the exterior of the door, a pair of rollbacks within the case for retracting said latch bolt, movable means connected to said knob and extending into the lock case and normally engaging both of said rollbacks to actuate the same upon rotation of the knob, means for dogging one of the rollbacks against actuation by the knob, and means for moving said movable means out of engagement with the dogged rollback, said last named means including a cylinder lock connected to said stem and mounted for movement in said knob to disengage said stem from the dogged rollback. 115
55. In a lock for a door or the like, a lock case, a latch bolt therein, a knob at the exterior of the door, a pair of rollbacks within the case for retracting said latch bolt, movable means connected to said knob and extending into the lock case and normally engaging both of said rollbacks to actuate the same upon rotation of the knob, means for dogging one of the rollbacks against actuation by the knob, and means for moving said movable means out of engagement with the dogged rollback, said last named means including a cylinder lock connected to said stem and mounted for movement in said knob to disengage said means from the dogged rollback, said cylinder lock including a key plug and means controlled by said key plug for controlling movement of the cylinder lock relatively to the knob. 120
60. In a lock for a door or the like, a lock case, a knob, a stem slidably connected to and

20. In a lock for a door or the like, a lock case, a latch bolt therein, a knob at the exterior of the door, a pair of rollbacks within the case for retracting said latch bolt, a stem connected to said knob and extending into the lock case and normally engaging both of said rollbacks to actuate the same upon rotation of the knob, means for dogging one of the rollbacks against actuation by the knob, and means for moving said stem out of engagement with the dogged rollback, said last named means including a cylinder lock connected to said stem and mounted for movement in said knob to disengage said stem from the dogged rollback, said cylinder lock including a bolt adapted to lock the cylinder lock against movement relatively to said knob, and a key plug controlling the operation of said bolt. 70
20. 21. In a lock for a door or the like, a lock case, a latch bolt therein, a knob at the exterior of the door, a pair of rollbacks within the case for retracting said latch bolt, a stem connected to said knob and extending into the lock case and normally engaging both of said rollbacks to actuate the same upon rotation of the knob, means for dogging one of the rollbacks against actuation by the knob, and means for moving said stem out of engagement with the dogged rollback, said last named means including a cylinder lock connected to said stem and mounted for movement in said knob to disengage said stem from the dogged rollback, said cylinder lock including a radially movable bolt adapted to lock said cylinder lock against movement relatively to said knob, a key plug, and a cam on said key plug engaging said bolt and adapted to control the movement of the latter. 75
20. 22. In a lock for a door or the like, a latch bolt, and operating mechanism for said latch bolt, said operating mechanism including manipulable means at the exterior of the door, means for dogging a part of said mechanism to prevent operation of said mechanism by said manipulable means, and means for releasing said manipulable means from control by said dogged part while maintaining the latter in dogged condition. 80
50. 23. In a lock for a door or the like, a latch bolt, and operating mechanism for said latch bolt, said mechanism including manipulable means at the exterior of the door, a stem for said means, said stem being movable with respect to said means, and means for locking said stem against operation of the operating mechanism in one position of the stem. 85
60. 24. In a lock for a door or the like, a latch bolt, and operating mechanism for said latch bolt, said operating mechanism including manipulable means at the exterior of a door, a stem for said means, said stem being movable relatively to said means and a part of the operating mechanism, and means engaging the stem in one position thereof with re- 90
- spect to the manipulable means to lock the latter against operation of the operating mechanism. 95
25. In a lock for a door or the like, a lock case, a latch bolt therein, a plurality of latch retracting elements within said case, a knob at the exterior of the door for operating said elements to retract said latch bolt, means for dogging one of said elements against operation by said knob, and key controlled means for releasing the knob from the dogged element to permit retraction of the latch bolt by said knob through another of said elements. 100
26. In a lock for a door or the like, a lock case, a latch bolt therein, a plurality of latch retracting elements within said case, a knob at the exterior of the door for operating said elements to retract said latch bolt, means for dogging one of said elements against operation by said knob, and key controlled means carried by said knob for releasing the knob from the dogged element to permit retraction of the latch bolt by said knob through another of said elements. 105
27. In a lock for a door or the like, a lock case, a latch bolt in said case, a knob having a stem movable relatively to the knob, latch retracting means having an operative connection with said stem, means for holding said retracting means against operation by said stem in one position thereof, said retracting means being freely operable by the stem in another position thereof, and means for moving said stem relatively to said knob. 110
28. In a lock for a door or the like, a lock case, a latch bolt in said case, a knob at the exterior of the door, said knob being provided with a stem, retracting mechanism in said case including a part normally rotatable with the stem, means for locking said part against movement by the stem, and means at the exterior of the door for disengaging the stem from said part. 115
29. In a lock for a door or the like, a lock case, a latch bolt in said case, a knob at the exterior of the door, said knob being provided with a stem, retracting mechanism in said case including a part normally rotatable with the stem, means for locking said part against movement by the stem, means at the exterior of the door for disengaging the stem from said part, and additional means operable by the stem when disengaged from said part for operating said retracting mechanism. 120
- In witness whereof, I have hereunto set my hand this 14 day of February, 1929.
- JOHN H. SHAW.
